(57) **CLAIM**

The ornamental design for a fluid transfer device, as shown and described.

DESCRIPTION

FIG. 1 is a front right perspective view from above of the fluid transfer device showing the new design;

FIG. 2 is a front right perspective view from below of the fluid transfer device showing the new design;

FIG. 3 is a front left perspective view from above of the fluid transfer device showing the new design;

FIG. 4 is a front left perspective view from below of the fluid transfer device showing the new design;

FIG. 5 is a top perspective view of the fluid transfer device showing the new design;

FIG. 6 is a bottom perspective view of the fluid transfer device showing the new design;

FIG. 7 is a front view in elevation of the fluid transfer device showing the new design;

FIG. 8 is a rear view in elevation of the fluid transfer device showing the new design;

FIG. 9 is a left side view in elevation of the fluid transfer device showing the new design;

FIG. 10 is a right side view in elevation of the fluid transfer device showing the new design;

FIG. 11 is a top view in plan of the fluid transfer device showing the new design; and,

FIG. 12 is a bottom view in plan of the fluid transfer device showing the new design.
